UNITED STATES PATENT OFFICE.

JOHN W. HAUBNER, OF FRIDAY HARBOR, WASHINGTON.

RECEPACLE-FEEDING MECHANISM.

1,118,766.

Specification of Letters Patent. Patented Nov. 24, 1914

Application filed July 7, 1913. Serial No. 777,738.

To all whom it may concern:

Be it known that I, JOHN W. HAUBNER, a citizen of the United States of America, and a resident of the city of Friday Harbor, in the county of San Juan and State of Washington, have invented certain new and useful Improvements in Receptacle-Feeding Mechanism, of which the following is a specification.

10 The present invention relates primarily to mechanisms of the above character especially adapted for feeding receptacles or other articles into machines for operation thereon by the latter, and it has for its main 15 object the provision of means which will be simple and durable in construction and efficient in operation.

Other objects will appear as my description progresses and those features of construction, arrangements and combinations 20 of parts on which protection is desired will be succinctly defined in the annexed claims.

In the drawings, wherein like characters 25 of reference indicate like parts throughout, Figure 1. is an elevation of the invention with parts in section and the machine to which it is applied broken away; Fig. 2. is a front elevation thereof; Fig. 3. is a top plan view of the mechanism; and Figs. 4 and 5. 30 are enlarged fragmentary views of the receptacle feeding mechanism taken from different view points.

Referring more in detail to the accompanying drawing, 1, denotes a support, 35 preferably being the machine to which the invention is applied. A table 2, suitably mounted on the support 1, is provided with a longitudinal groove or guide 3, for a belt 4, which latter is driven from any source of 40 power supply and forms a carrier for the receptacles 5. The receptacles, which are shown in the shape of cans are advanced by the belt in to the path of movement of a receptacle removing or feeding member 6, 45 which removes the cans transversely of the belt in to a suitable guideway 7, of the machine 1. Feeder 6, is slidable in slot 8 of upright 9, and connected pivotally to lever 10, fulcrumed on bracket 11, which lever is 50 connected by link 12 to arm 13, of a suitably journaled rock shaft 14. A second arm 15, on rock shaft 14, carries a friction roller 16, which is normally held by spring 18, against a double cam 17 rotated by a drive chain

(not shown) taking over sprocket 19. 55 When cam portion 17' acts on arm 15, the receptacle removing member 6, is withdrawn to the dotted line position in Fig. 5, in which position said feeder is retained by gravity lock 20, engaging in recess 21, provided in the upper edge thereof. The lock is carried by arm 22 of sleeve 23, mounted for oscillatory movement and comprises substantially an L shaped member, the toe 20' of which forms a stop which permits of sufficient movement being imparted to the lock to release the feeder. A trip arm 24, projects from arm 22, into the path of movement of the cans 5, on the belt for engagement by a can. The lock 20, is adapted to 70 engage the upright 9 for reinforcement when locking the feeder 6, should the spring 18, be of great strength. As the can strikes the trip arm or immediately thereafter, in which case the belt continues its movement 75 beneath the can, the cam portion 17'' acts on arm 15, to overcome the tension of the spring 18, whereby a slight movement of the can by the belt will raise the lock 20, from recess 21, and permit the feeder to eject or 80 move the can into guideway 7, upon continued rotation of the cam. In this connection it must be noted that the roller 16, riding down the cam faces will regulate and control the movement of the feeder. 85

One wall of guideway 7, extends over the belt, as at 7', to provide a positive stop for the cans. This is essential especially if a can is disposed on its side rather than in an upright position, in which former instance 90 the can will not trip the arm 24, and hence will not be fed into the machine. Thus it will be observed that the cans will always be fed into the machine in an upright position. 95

Having thus described my invention, what I claim as new and desire to secure by Letters Patent of the United States of America, is:

1. In mechanism of the character described, a carrier, a stationary support, removing means on the support adapted for movement for engagement with the article supported on the carrier, means for operating the removing means, and means for locking the removing means from movement. 100

2. In mechanism of the character described, a carrier, a stationary support, a

- feeder mounted on the support for movement and adapted to engage the article supported on the carrier for removing the same, and means for locking the feeder from movement.
5. In mechanism of the character described, a carrier, a feeder mounted for movement and adapted to engage the article supported on the carrier for removing the same, and locking means for locking the feeder from movement and operable by the article supported on the carrier to release the feeder.
10. In mechanism of the character described, a carrier, a movable feeder, means locking the feeder from movement in one direction, said means being releasable by an article on the carrier, and means preventing the releasing of the locking means between predetermined intervals of time.
15. In mechanism of the character described, a continuously driven carrier, a movable feeder, means locking the feeder from movement, said means being releasable by an article on the carrier, and means preventing the releasing of the feeder by an article engaging the locking means between predetermined intervals of time.
20. In mechanism of the character described, a movable feeder adapted to engage a receptacle when disposed in the path of movement thereof, means for moving the feeder, and means for locking the feeder from movement releasable by the article when placed in the path of the feeder.
25. In mechanism of the character described, a support, a relatively movable carrier, a feeder on the support for removing articles from said carrier, and means for locking the feeder from movement releasable automatically during movement of the carrier.
30. In mechanism of the character described, a support, a relatively movable carrier, a feeder movable transversely of the carrier, and means for locking the feeder from movement releasable by an article on the carrier.
35. In mechanism of the character described, a movable feeder adapted to engage a receptacle when disposed in the path of movement thereof, means normally tending to retain the feeder at one limit of its travel, and means for moving the feeder against the action of the first named means and adapted to control the movement of the feeder when acted upon by the first named means.
40. In mechanism of the character described, a movable feeder adapted to engage a receptacle when disposed in the path of movement thereof, resilient means normally tending to retain the feeder at one limit of its travel, and means for moving the feeder against the action of the first named means and adapted to control the movement of the feeder when acted upon by the first named means.
45. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
50. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
55. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
60. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
65. In mechanism of the character described, a support, a carrier, a feeder, means for locking the feeder in an inoperative position, means for moving the feeder to an operative position when acted upon by the first named means.
70. In mechanism of the character described, a support, a carrier, a feeder for removing an article from the carrier, and means for moving the feeder including a cam and a yielding means, the latter permitting of the feeder yielding when resisted beyond a certain degree.
75. In mechanism of the character described, a support, a carrier, a feeder for removing an article from the carrier, cam means for controlling the movement of the feeder, and resilient means normally tending to retain the operative connection between the cam means and feeder.
80. In mechanism of the character described, a support, a carrier, a feeder on the support for engaging an article on the carrier, means normally tending to retain the feeder toward one limit of its travel, means for moving the feeder toward its opposite limit of travel, and means for locking the feeder from movement by the first means.
85. In mechanism of the character described, a support, a carrier, a feeder on the support for engaging an article on the carrier, yielding means normally tending to retain the feeder toward one limit of its travel, means for moving the feeder toward its opposite limit of travel, and means for locking the feeder from movement by the first means.
90. In mechanism of the character described, a support, a carrier, a feeder on the support for engaging an article on the carrier, yielding means normally tending to retain the feeder toward one limit of its travel, means for moving the feeder toward its opposite limit of travel, and means for locking the feeder from movement by the first means.
95. In mechanism of the character described, a support, a carrier, a feeder on the support for engaging an article on the carrier, means normally tending to retain the feeder toward one limit of its travel, means for moving the feeder toward its opposite limit of travel, and means operable during movement of the carrier for locking the feeder from movement by the first means.
100. In mechanism of the character described, a support, a carrier, a feeder on the support for engaging an article on the carrier, means normally tending to retain the feeder toward one limit of its travel, means for moving the feeder toward its opposite limit of travel, and means operable during movement of the carrier for locking the feeder from movement by the first means.
105. In mechanism of the character described, a support, a carrier, a feeder on the support, resilient means tending to retain the feeder in an operative position, means for moving the feeder to an inoperative, and means for locking the feeder in the latter position.
110. In mechanism of the character described, a support, a carrier, a feeder on the support, resilient means tending to retain the feeder in an operative position, means for moving the feeder to an inoperative, and means for locking the feeder in the latter position.
115. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
120. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
125. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.
130. In mechanism of the character described, a support, a carrier, a feeder, means for locking the feeder in an inoperative position, means for moving the feeder to an operative position when released, and a trip arm for releasing the feeder from the locking means, said arm being spaced from the carrier to be engaged only by an article properly positioned on the carrier.

position when released, and trip means operable by and during movement of an article on said carrier for releasing the feeder.

operative position, means for locking the feeder from movement, and spring means for moving the feeder to an operative position when released, said cam means controlling the movement of the feeder to the last named position. 15

19. In mechanism of the character described, a carrier, a feeder, continuously driven means for controlling the movement of the feeder, and means for locking the feeder from movement to permit of the carrier positioning an article for the feeder.

Signed at Friday Harbor, Wash., this 30th day of June, 1913.
